BRUNO C. LECHLER, OF PHILADELPHIA, PENNSYLVANIA, ASSIGNOR OF ONE-HALF TO FLETCHER WORKS, INCORPORATED, OF PHILADELPHIA, PENNSYLVANIA, A CORPORATION OF PENNSYLVANIA.

APPARATUS FOR TREATING SUGAR.

Application filed January 15, 1921. Serial No. 437,486.

To all whom it may concern:

Be it known that I, BRUNO C. LECHLER, a citizen of the United States, and a resident of Philadelphia, in the county of Philadelphia and Commonwealth of Pennsylvania, have invented certain new and useful Improvements in Apparatus for Treating Sugar, of which the following is a specification.

10 My invention relates to an improved method of and apparatus for treating sugar and an object of the invention is a reduction in the loss in centrifugal sugars due to inversion during storage and transportation.

15 Centrifugal sugars, as is well known, are subject to gradual deterioration, depending upon the degree of moisture present and bacterial and mold contamination at the time of bagging. As the sugar magma is sterilized by heat incidental to the formation of the sugar crystals in a vacuum pan and thereafter is immediately separated into centrifugal sugar and molasses, and as this sugar when bagged has but a limited opportunity to absorb either moisture or bacteria from the surrounding air, it is desirable to reduce or prevent the contamination of the sugar during the period beginning when the magma leaves the centrifugal and ending

30 when it is bagged.

With the existing apparatus the centrifugals acting as fan rotors, draw great quantities of air into the centrifugal casing, a portion of which is necessarily drawn through the sugar, thus carrying away moisture and increasing the dryness of the sugar crystals but in this operation any spores contained in the air drawn through the sugar are deposited upon the wet faces of the crystalline mass. In practice this air is drawn in chiefly at the bottom of the casing and therefore comes in contact with air close to the floor and which has been shown to contain the largest percentage of these spores. These spores are of several types common in the raw cut cane and in the soil and are subject to propagation in stagnating masses of sweet water or molasses drippings on the floor.

Existing centrifugals cannot be enclosed in an air-tight casing because means must be provided for charging massecuite and removing molasses and sugar. Furthermore, the centrifugal spindle passing into the casing necessarily possesses a certain amount of

lateral motion. Even were it feasible to encase the entire centrifugal, provision would still have to be made for charging the massecuite, extracting the molasses, removing the sugar and cleaning the lining of the centrifugal, all of which requires frequent access to the machine and prevents the use of any elaborate devices requiring a considerable number of operations in placing the same in position and removing the same to permit access to the centrifugal.

In the device of this invention no attempt is made to seal the centrifugal within its casing and although I prefer to provide the casing with hinged, sectional covers closing the top opening and thus reducing the access of air to the centrifugal, no effort is made to seal the sugar or molasses discharge openings.

It is the purpose of the present invention to arrange my apparatus whereby air will be drawn into the same from a point removed as far as possible from contamination, such as the upper part of the centrifugal room where the air is comparatively undisturbed, or from without the room entirely, means having been provided whereby this air will be maintained free from contamination.

By my improved method and apparatus the air is drawn into the centrifugal by utilizing the action of the centrifugal which acts as a fan rotor, this air being discharged through the molasses spout. Furthermore, by my improved method and apparatus not only is the air drawn into the centrifugal maintained free from contamination, but the sugar being discharged from the centrifugal is carried against this stream of air in a closed passage leading from the centrifugal, the sugar in passing through this passage being broken up into separate crystals so that each crystal is air dried.

Inasmuch as in a centrifugal the drying of the crystals is realized by the physical throwing off of moisture drops from the interstices between the crystals, hygroscopically or capillary retained moisture is but imperfectly removed and this small remaining trace is removed to a much better advantage by a dry current of air. It will be seen, therefore, that by my improved method and apparatus both the spore contamination and degree of moisture are reduced.

Broadly, therefore, my invention relates to a process for purging sugar which consists in subjecting the sugar magma to centrifugal force in a substantially sterile atmosphere, the sugar thereafter being transported in a substantially uncontaminated atmosphere to a storage bin and if desired the uncontaminated atmosphere may be heated.

Obviously the type of apparatus employed 10 for performing this process may be varied within wide limits and to this end it is to be understood that the apparatus illustrated in the accompanying drawing is merely illustrative and not definitive.

15 Referring to the accompanying drawing, 1 designates a centrifugal basket driven from a drive shaft 2 by a suitable motor 3, the centrifugal being surrounded by a casing 4. The centrifugal or centrifugal basket is provided at its top with an opening 5 through which the masscuite is charged to the basket and an opening 6 in the bottom thereof through which the sugar is discharged from the basket, this opening being controlled by 20 a cover 7. The sides of the basket are perforated as indicated at 8 to allow the discharge of molasses from the basket between the basket and the casing 4, this molasses being 25 discharged from the apparatus at the discharge spout 9.

The casing 4 is provided with a sectional cover 10 and material is charged into the basket from a supply tank 11, the discharge of material from this basket being controlled 30 by a valve 12. Steam is admitted to the centrifugal by means of a steam pipe 13, the supply of steam to the centrifugal being controlled by a valve 14. The lower part of the casing 4 is connected with a closed passageway 15, in the present instance directly beneath the discharge opening 6 of the centrifugal basket, this passageway in operation being in communication with a closed passageway 16, the latter leading to a storage room or bin 17 from which the sugar is conveniently discharged into bags 18. The closed passageway 15 is provided with a conveyer 19 driven by a motor 20, this conveyer being provided for the purpose of 40 transporting sugar to the closed passageway 16 within which I provide an elevator 21 driven from any suitable source of power, and adapted to receive the sugar from the conveyer 19 and elevate it to the storage bin 17. The storage bin is provided with a pipe 22 which may be located adjacent the top of the centrifugal room or connected to the outside atmosphere. The purpose of providing the pipe 22 is to insure that a supply 50 of uncontaminated air will be drawn into the centrifugal instead of taking the air from that portion of the room in proximity to the centrifugal as is usually done with apparatus now employed. If desired, steam pipes 23 may be provided near the pipe 22

so that the air drawn into the apparatus may be heated. It is to be understood that the passageways 15 and 16 are closed and that all air drawn into the centrifugal must pass through these closed passageways and likewise that sugar passing from the centrifugal to the storage bin 17 must travel through these closed passageways also. It is to be understood furthermore that while I have illustrated a bin, et cetera, it may at times be feasible to discharge the sugar directly from the bottom of the casing 4 to some other point where the air is substantially uncontaminated and from which the air passes back through the centrifugal against the outgoing stream of sugar.

In operation the sections of the cover 10 of the casing are raised and the centrifugal basket 1 is charged with the sugar magma from the storage tank 11 and the covers 55 closed. The centrifugal is then brought to speed whereupon the molasses is thrown out through the perforations 8 in the side walls of the centrifugal basket, caught in the outer casing and carried off through the spout 9. 90 While the centrifugal is still in operation a jet of dry steam is passed into the centrifugal through the steam pipe 13, this jet serving both to sterilize and heat the sugar and to cause the film of molasses or mother liquor 95 adhering to each crystal to become more fluid and pass off more easily.

After a sufficient period of time the valve 14 in the steam pipe 13 is closed, thus shutting off the supply of steam to the centrifugal, the centrifugal basket however continuing to rotate and drawing in through the outlet 6 of the basket quantities of uncontaminated or sterile air from the upper part of the bin 17 through the closed passageways 100 16 and 15. This air which may be slightly heated if desired, being drawn through the sugar in the centrifugal basket will serve to carry away the moisture in the basket remaining from the condensed steam and leave 110 the crystals in as dry a condition as possible. The centrifugal is then stopped, the covers 105 opened, the cover or valve 7 at the bottom lifted and the sugar discharged through the opening 6 in the closed passageway 15 upon the conveyer. The centrifugal may then be charged again and while in operation, the sugar in the passageway 15 will be agitated by the conveyer 19 and gradually conveyed 120 to the closed passageway 16 where it will be lifted by the elevator 21 and carried up and discharged into the bin 17, the sugar in passing from the centrifugal to the bin being subjected to the sterile air passing from the pipe 22 to the centrifugal, further drying of the sugar being effected for this reason and the sugar finally being bagged from the bin 17 directly, without further contact with spore laden air.

130 It will be seen, therefore, that I have pro-

vided a process for purging sugar whereby the sugar is treated and bagged in an atmosphere substantially free of spores and that, therefore, the danger of inversion of the sugar during storage and transportation is eliminated.

What I claim is:

1. In an apparatus for purging sugar, in combination, a centrifugal provided with a casing which has separate charging and discharging openings, and means for preventing the entry of contaminated air to the centrifugal during operation of the same and during the discharge of material from the centrifugal.

2. In an apparatus for purging sugar, in combination, a centrifugal provided with a casing having both a charging and a discharging opening, means connecting one of said openings with a source of substantially uncontaminated air, said openings in the casing being so proportioned and disposed relative to the centrifugal as to cause the latter to draw air into the centrifugal through the opening connected with a source of uncontaminated air.

3. In an apparatus for purging sugar, in combination, a centrifugal provided with a casing, and an enclosed passageway leading from an opening in the centrifugal casing and communicating with a supply of substantially uncontaminated air.

4. In an apparatus for purging sugar, in combination, a centrifugal provided with a casing having charging and discharging openings, means for closing the charging opening, means for supplying dry steam to the contents of the centrifugal basket and an enclosed passageway leading from the discharging opening through which passageway dried material leaves the centrifugal and uncontaminated air enters the centrifugal.

5. In an apparatus for purging sugar, in

combination, a centrifugal and a centrifugal 45 casing having discharge openings, a storage bin, a closed passageway leading from said discharge openings to said storage bin, a screw conveyer and an elevator cooperating therewith for transporting sugar crystals 50 from the centrifugal discharge opening to the storage bin through said closed passageway, and means for drawing uncontaminated air through said passageway in a direction opposed to the direction of travel of 55 the sugar crystals through the passageway.

6. In an apparatus for purging sugar, the combination of a centrifugal and a centrifugal casing, a storage bin in communication with a supply of substantially uncontaminated air, a closed passageway connecting the centrifugal to the storage bin, means for conveying sugar crystals from the centrifugal through said storage passageway to said bin against a current of uncontaminated 60 air passing from the bin to the centrifugal and means for heating said current of air.

7. In an apparatus for purging sugar, the combination of a centrifugal and a centrifugal 70 casing, a storage bin communicating with a supply of uncontaminated air, means for heating said air, a closed passageway connecting the centrifugal and centrifugal casing with said storage bin, means in said 75 passageway for breaking up the sugar crystals discharged into the same from said centrifugal, and means in said closed passageway for conveying the sugar crystals after the same have been broken up to said 80 storage bin, a current of uncontaminated, heated air from the supply bin passing through the mass of sugar crystals as the same is being conveyed to the storage bin.

This specification signed this 14 day of 85 January 1921.

BRUNO C. LECHLER.
